H. TILL.

CAN OPENER.

APPLICATION FILED JUNE 1, 1920.

Patented Oct. 4, 1921.

INVENTOR.
Henry Till
BY *Bernard Webster*
ATTORNEY

UNITED STATES PATENT OFFICE.

HENRY TILL, OF PITTSBURG, CALIFORNIA.

CAN-OPENER.

1,392,466.

Specification of Letters Patent.

Patented Oct. 4, 1921.

Continuation of applications Serial No. 335,355, filed November 3, 1919, and Serial No. 346,025, filed December 18, 1919. This application filed June 1, 1920. Serial No. 385,527.

To all whom it may concern:

Be it known that I, HENRY TILL, a citizen of the United States, residing at Pittsburg, in the county of Contra Costa, State of California, have invented certain new and useful Improvements in Can-Openers; and I do declare the following to be a full, clear, and exact description of the same, reference being had to the accompanying drawings, and 10 to the characters of reference marked thereon, which form a part of this application.

This invention relates to improvements in can-openers, and is particularly intended to be a continuation of my co-pending applications Serial No. 335,355, filed November 3rd, 1919, and Serial No. 346,025, filed December 19th, 1919.

The principal object of my invention is to provide a can opener having two different 20 cutting members, each being designed for use on that type of can to which it is best adapted, so that with my device any type of can, whether circular, rectangular or other shape, and of any size, may be readily and 25 easily opened with a minimum of effort on the part of the user.

I have also provided a simple attachment for holding one of the cutting members out of the way of the other and inactive when 30 the latter is being used.

A further object is to provide an article having a minimum of parts, which are arranged in such a manner that the cleaning 35 of the device after use is an easy task, since there are no narrow crevices in which food, etc., may collect and become stale by reason of the user's inability to easily wash the can-opener.

A further object of the invention is to 40 produce a simple and inexpensive device, and yet one which will be exceedingly effective for the purposes for which it is designed.

These objects I accomplish by means of 45 such structure and relative arrangement of parts as will fully appear by a perusal of the following specification and claims.

In the drawings similar characters of reference indicate corresponding parts in the 50 several views.

Figure 1 is a side elevation of my improved can-opener, partly in section, showing one of the cutting elements operating on a sanitary can.

55 Fig. 2 is a perspective view of the same.

Fig. 3 is a fragmentary perspective view showing the other cutting element operating on a rectangular can.

Fig. 4 is a plan view of the cutting element shown in Fig. 3.

Referring now more particularly to the characters of reference on the drawings, the numeral 1 denotes a hardened steel circular shank of suitable length, on one end of which is fitted a handle 2 of any suitable material.

The other end of the handle is bent at right angles to form a short arm 3, from which extends a flat member 4 parallel to the shank.

The plane of this member is at right angles to the arm 3, and both side edges are curved from the arm 3 to a point at the outer end. Both such edges are beveled on the face away from said arm to form opposed cutting edges 5.

The outer edges of the arm 3 are preferably sharp as shown at 6, so that when this cutter portion is used to open a can 7 of the type shown in Fig. 3, one or the other of the sharp edges of the arm will bite into the edge of the can and form a non-slipping fulcrum for the cutting element when a downward pressure is exerted on the shank.

Slidable and rotatable on the shank 1 is a rotary cutter 8, which comprises a sharp 85 edged and hardened circular cutting disk 9, preferably cup-shaped in cross section, and having a sharp edged and pointed lip 10 projecting from the periphery of the disk at any point thereon, and in the same plane 90 as the cutting edge thereof.

The disk 9 is concave relative to the outer end of the shank, and for a portion of its area extends at right angles to the shank, as at 11. Spaced from this portion of the 95 cutting disk and approximately the same size thereas is a guide disk 12, to which is fixed or formed integral therewith a roller 13 extending between the cutting and guide disks, and adapted to bear on the rim 14 of 100 a can 15 of the sanitary type.

My can opener is particularly intended for the now almost universal "sanitary" cans, all of which have such a rim 14. The two parallel disks 11 and 12 straddle the 105 rim, and positively prevent the cutter from any tendency to swerve from a true path.

Adjacent the disk 9 this roller is shoudered as at 16 to form an abutment for said disk, the latter slipping thereover, and the 110

roller member being then headed over to clench the disk into place.

The guide disk 12 is flattened or cut away on a chord for a portion of its periphery, 5 as shown at 17, for a purpose as will appear.

Fixed to the ferrule 2* of the handle is a flat strip 18 projecting substantially at right angles to the shank, and extending 10 away therefrom a distance slightly greater than the radius of the guide disk 12. The strip is then bent toward the shank as at 19, and terminates along a line the same distance from said shank as the flat edge 15 17 of the disk 12 therefrom.

This member serves as a clip or catch to hold the rotary cutter from sliding on the shaft, in which case the flat portion 17 of the guide disk passes over the portion 19 of 20 the clip, and by then turning the member 8 somewhat, it is prevented from sliding movement.

The edge of the clip is curved horizontally on about the same center as the neck 25 of an ordinary bottle and is so shaped and positioned relative to the shank that it may also be used as a bottle-cap remover, by applying the edge of the clip under the cap, and lifting upon the handle, the shank 30 resting on the cap as a fulcrum.

A short distance from the pointed member 4 the shank is flattened to form shoulders 20, in this manner preventing the cutter 8 from sliding down too close to the end.

35 When using the rotary cutter, the center of the can is first punctured by holding the shank vertically and pressing the pointed member 4 into the center of the can, the shoulders 20 preventing the rotary cutter 40 from sliding down onto the member 4 and interfering with the vision and the manipulation of the same. The cutter 8 is then moved into position so that the roller bears on the rim 14 of the can, and rotated so that 45 the lip 10 is adjacent the top of the can. A slight downward pressure on the handle will be sufficient to cause the lip to puncture the can and provide an initial orifice which is then readily enlarged by the action 50 thereon of the main body of the cutter.

By then pressing the handle 2 forward and downward, the cutter will rapidly cut through the top of the can, the member 4 bearing up on the under side of the top 55 as a fulcrum, and the arm 3 serving as a pivotal point for the movement of the handle.

When utilizing the member 4 as a can-opening element, the rotary cutter is held 60 up out of the way by means of the clip on the handle, as aforesaid.

From the foregoing description it will be readily seen that I have produced such a device as substantially fulfills the object of the invention as set forth herein.

65 While this specification sets forth in detail the present and preferred construction of the device still in practice such deviations from such detail may be resorted to as do not form a departure from the spirit of 70 the invention, as defined by the appended claims.

Having thus described my invention what I claim as new and useful and desire to 75 secure by Letters Patent is:

1. A can opener comprising a shank, a rotary cutting disk thereon, and a sharp edged and narrow lip projecting from the periphery of the cutter and in the same plane as the cutting edge thereof.

80 2. A can opener comprising a shank having an offset and sharp end adapted to pierce the center of the top of a can, a handle on the other end, a rotary cutter slideable and turnable on the shank, a guide 85 disk formed with the cutter, and a clip secured to the handle and adapted to engage the disk to hold the cutter against sliding.

3. A can opener comprising a relatively 90 long shank having an offset and sharp end adapted to pierce the center of the top of a can, a handle on the other end, a rotary cutter slideable and turnable on the shank, a guide disk formed with the cutter, said 95 disk being flattened for a portion of its periphery, and a rigid clip depending from the ferrule of the handle and having its outer end bent to extend toward the shank, the distance from the shank to said bent portion of the clip being the same as that from the shank to the flat edge of the disk, whereby the latter may be slid onto the clip, and then turned slightly to hold the cutter from 100 sliding on the shank.

105 4. A can opener comprising a shank having an offset and sharp end adapted to pierce the center of the top of a can, a handle on the other end, a rotary cutter slideable and turnable on the shank, and means whereby 110 when the cutter is moved adjacent the handle and rotated slightly it will be firmly held against sliding on the shank.

115 5. A can opener comprising a shank, a rigid handle on one end thereof, a rotary cutter slideable and turnable on the shank, a guide member fixed to the cutter, and a clip secured to the handle and adapted to engage the guide member to hold the cutter against sliding movement.

120 In testimony whereof I affix my signature.
HENRY TILL.
